ELECTRIC CONNECTOR PLUG

Gustaf E. Andre, Richmond, Ind., assignor to
Belden Manufacturing Company, Chicago, Ill.,
a corporation of Illinois

Application May 3, 1937, Serial No. 140,421

4 Claims. (Cl. 173—361)

This invention relates to electric plug connectors and more particularly to the male type of plug connectors which are commonly used for connecting various electrical appliances and apparatus to a wall outlet or other similar source of electrical energy.

The main objects of the invention are to provide a male connector plug which when inserted in an outlet socket will establish good electrical connections between the terminals of the outlet socket and the conductor wires of the electrical cord which carries the plug; to provide a connector plug of the type indicated which will fit and make good electrical contact with outlet sockets of both present day construction and older constructions which are now more or less abandoned, but many of which remain in older buildings; to provide a plug connector of the type indicated which will have a tendency to more or less lock itself in place in both new and old type outlet sockets; to provide a connector which will be simple and low in cost of construction, but which will be rugged, durable and efficient in operation; and in general, it is the object of the invention to provide an improved electric connector plug of the type indicated.

Other objects and advantages of the invention will be understood by reference to the following specification and accompanying drawing, where in there is illustrated a male type connector plug embodying a selected form of the invention and also the manner in which it cooperates with new and old type electric outlet sockets.

In the drawing:

35 Figs. 1 and 2 are, respectively front and side elevations of the selected form of the improved connector plug.

Fig. 3 is a perspective of a portion of a contact prong element of the improved structure.

40 Fig. 4 illustrates the cooperative relationship of the improved connector plug with an outlet socket, embodying contact elements which are typical of present day types of outlet sockets, and

Figs. 5 and 6 are front and side views, respectively, (partially in section) illustrating the cooperative relationship between the improved connector plug structure and an outlet socket embodying contact elements typical of old style outlet sockets. The plane of the section of the socket structure shown in Fig. 5 is substantially indicated by the line 5—5 on Fig. 6, and the plane of the section of the socket structure shown in Fig. 6 is substantially as indicated by the line 6—6 on Fig. 5.

55 The improved connector plug structure shown

in Fig. 1 comprises a main body element 10 which may be of soft rubber in accordance with present day preferred practice, and contact prongs 11 and 12, respectively. The contact prongs extend into the body and have their inner end portions 13, 13 suitably seated and anchored in the plug body so as to prevent withdrawal of the prongs. The body 10 may be of one-piece molded construction, molded in place about the inner end portions 13, 13 of the contact prongs or the said body may comprise one or more parts molded or otherwise formed independently of the contact prongs, and subsequently assembled with the contact prongs. Also, the body may be of hard or rigid material such as Bakelite, since the softness or inherent resiliency of the rubber plug body which is preferred is not required for the purposes of the plug construction herein contemplated.

An electric conductor cord 14, in this instance a 20 duplex cord, has its conductor wires 15, 15 respectively connected within the body 10 to the inner end portions of the contact prongs. Any desirable means may be employed for anchoring the cord to the plug body so as to prevent 25 excessive strain on the wire itself or connections of the wire with the contact prongs. Since such details are not material to the present invention they are not illustrated.

As indicated in Fig. 1, the inner end portions 30 13, 13 of the prongs are substantially straight. They may, however, be bent or shaped in any manner which will lend itself to the selected plug body construction.

The exposed or outer portions of the contact 35 prongs 11 and 12 are substantially alike, except that they are reverse in respect of the bends or shaping. Each contact prong is bent inwardly as indicated at 16 adjacent the front end of the plug body so as to provide short, angularly, inwardly extending portions 17, 17. The prongs are again bent as indicated at 18 so that the main lengths of the exposed prong portions extend slightly or gradually outwardly so that their free ends are spaced somewhat more than the portions indicated at 19, 19 adjacent the bends 18.

At their free ends 20, 20, the prongs are each provided with an outwardly projecting hump 21 which, as clearly shown in Figs. 2 and 3, is in the form of a transversely extending outwardly 50 projecting bead. The free ends of the prongs preferably, but not necessarily, have their corners beveled or chamfered as indicated at 22, 22, and short, longitudinally extending beads or ribs such as indicated at 23 are pressed outwardly 55

from the prongs. As shown, the longitudinally extending ribs 23 are disposed substantially centrally of the width of the respective prongs and the said ribs are so formed that their outer surfaces are substantially flush with the outer surfaces of the transverse beads 21 and gradually taper to and merge with the normal faces or surfaces of the respective contact prongs.

The contact prongs 11 and 12 may be easily produced by simple stamping or punch press operations and they may be made from suitable material such as brass. They are preferably formed of spring brass of considerably less thickness than is conventionally used in forming the contact prongs of conventional connector plugs. Satisfactory results have been obtained by employing contact prongs made of material approximately one-thirty-second of an inch in thickness, the width of the prongs being approximately one-quarter of an inch, which latter dimension is substantially standard.

In outlet sockets of present day conventional style, there is usually provided relatively thin sheet metal terminal members such as indicated at 24, 24 (Fig. 4), the same having rebent inner portions 25, 25 which are equipped adjacent their free ends with inwardly extending bosses or protuberances as indicated at 26. Such terminal elements are housed within an enclosure made of suitable insulating material usually hard and rigid in form, although not necessarily so. In Fig. 4, the socket terminals 24, 24 are shown as being those of a screw type plug which is provided for the purpose of converting an ordinary lamp socket or so-called Edison base socket into a female socket for receiving a male connector plug. It will, however, be understood that the contact members 24, 24 illustrated in Fig. 4 are intended to typify the conventional practice in present day wall and like outlets. In the various forms of outlets typified by the outlet of Fig. 4, the contact prongs are usually separated by an intermediate portion 27 of insulating material which is usually integral with the socket body, and the front end of the socket body is equipped with openings such as indicated at 28, 28, through which the connector plug contact prongs 11 and 12 may be inserted into the socket.

As indicated in Fig. 4, the portions 19, 19 of the connector plug contact prongs are adapted to engage the opposite faces of the socket portion 27 so as to be thereby urged outwardly to spread the free ends 28, 28 of the contact prongs. The spreading of the contact prongs, in a hard-bodied plug involves flexing of the prongs alone, but in the preferred form in which the body 10 is made of resilient material, the body itself yields to a limited extent so that less flexing of the metal prong is required.

Spreading of the contact prongs 11 and 12 insures the making of good electrical contact between the inner end portions thereof and the free end portions of the rebent parts 25, 25 of the socket terminals. The arrangement is preferably such that the contact is effected between the protuberances 26, 26 and the outside faces of the respective prongs 11 and 12, and such that the free ends of the rebent terminal portions 25, 25 do not bear on the contact prongs. Also, as indicated in Fig. 4, the arrangement is such that the longitudinally extending rib portions 23, 23 of the contact prongs are in their entireties disposed inwardly of the said protuberances 26, 26, so that upon withdrawal of the connector plug from the socket, the said ribs 23, 23 will engage said pro-

tuberances to effect a gradual camming of the rebent terminal portions 25, 25 laterally outwardly incident to the endwise withdrawal of the prongs of the male connector plug. By this means there will be no scraping or gouging of the surfaces of the connector prongs by the relatively sharp edges of the free ends of the rebent terminal portions. Also, it will be observed that because of the spreading effect of the engagement of the prong portions 19, 19 with the socket body 10 portion 27, the ribs 23, 23 have a definite tendency to resist withdrawal of the connector plug, in other words, to more or less snap-lock the plug in connected relation to the socket.

In Figs. 5 and 6, the outlet socket structure typifies the majority of old style outlet sockets which are found in existence in older buildings. In such outlet sockets there are usually two sets of three terminal elements, each set comprising oppositely disposed terminal parts 29 and 30, and a third terminal element 31 which extends transversely of the terminal parts 29 and 30. As indicated in Fig. 6, the oppositely facing terminal elements 29 and 30 include substantially parallel portions 32 which have their free ends flared to provide an entrance mouth. At the inner ends of the said parallel portions 32, 32 the said terminals have oppositely diverging, angularly extending portions 33, 33 which are integrally connected to a base portion 34. The third member 31 of each of said sets of elements is also integrally connected with said base substantially as indicated in Fig. 5. The details of construction of the third element terminals varies somewhat in different manufacturers' old style sockets, but practically all of them included an arrangement which provided parallel portions such as indicated at 32, 32, oppositely diverging portions such as indicated at 33, 33, and a transversely extending portion 34. As indicated in Fig. 6, the transversely extending bead portion 21 of each contact prong of the male connector plug fits against the inside faces of the diverging portions 33, 33, it being noted that the transversely extending bead 21 has its inner faces angularly disposed as clearly indicated in Figs. 2, 3 and 6. The angular arrangement of the inner faces of the transverse beads 21 is such that it substantially coincides with the average angular position of the portions 33 so that the said beads tend to lock behind said angular terminal portions. The longitudinally extending rib portion 23 of each prong more or less fits in the normal spacing between the parallel portions 32 of the socket terminal elements. The transversely extending terminal element 31 engages the inside of the straight intermediate portions of the prong members 11 and 12, as shown in Fig. 5, and an intermediate portion 35 of the socket body material engages the portions 19, 19 of the contact prongs to effect spreading of the latter substantially as previously described.

It will be observed that in the old style socket construction typified by Figs. 5 and 6, the spreading effect produced on the contact prongs of the connector plug causes the establishment of good electrical connection between the humped free ends of the contact prongs and the angular portions 33, 33 of the socket terminal elements. Such connection may in most instances be also enhanced by the backing provided by the transversely extending element 31 which also makes direct electrical contact with the inner faces of the respective contact prongs.

It will be observed that the improved construction embodies a relatively simple form of

contact prong which may be stamped by an ordinary and simple punch-press operation. Hence the cost of producing the prong is very low. Also, because of the thinner weight of metal employed in making the improved contact prongs, the cost thereof is somewhat reduced over the cost of the heavier contact prongs employed in conventional constructions, even though a slightly more expensive grade of metal be employed. The spring characteristic of the metal employed in contact prongs need not be very strong. It may be relatively light since the structure of the socket itself tends both to spread the contact prongs and to resist their spreading. The spreading effect is of course that produced by engagement of the prong portions 19, 19 and the resistance to spreading occurs where the contact prongs engage the terminal elements of the socket.

Changes in the described construction may be made without departing from the spirit of the invention, the scope of which should be determined by reference to the following claims, the same being construed as broadly as possible consistent with the state of the art.

I claim:

1. An electric connector plug comprising a body of insulating material and a pair of contact prongs carried by said body and projecting from the front end thereof, said prongs each having rear portions adjacent the body arranged in forwardly converging relationship to each other and, beyond said converging portions, front portions of substantially straight form disposed in forwardly diverging relationship, the free ends of each prong being provided with a transversely extending detent rib and a second detent rib extending at an angle to the first-named rib and positioned inwardly from said first-named rib, said ribs adapted to cooperate respectively with corresponding detent portions of two different types of electrical outlets.

2. An electric connector plug comprising a body of insulating material and a pair of contact prongs carried by said body and projecting

from the front end thereof, said prongs each having rear portions adjacent the body arranged in forwardly converging relationship to each other and, beyond said converging portions, front portions of substantially straight form disposed in forwardly diverging relationship, each of the front portions of said prongs being provided adjacent their forward ends with a lateral offset adapted to cooperate with a portion of a predetermined type of electrical outlet for resisting withdrawal of the connector plug therefrom, and each of said front portions being provided with a second offset spaced longitudinally from said first mentioned offset and adapted to cooperate with a portion of another type of electrical outlet for resisting withdrawal of the connector plug from such other type of outlet.

3. An electric connector plug comprising a body of insulating material and a pair of contact prongs carried by said body and projecting from the front end thereof, said prongs each having rear portions adjacent the body arranged in forwardly converging relationship to each other and, beyond said converging portions, front portions of substantially diverging relationship, the front portions of said prongs adjacent their forward ends being provided with inwardly facing transverse offsets and longitudinal beads, the latter being disposed centrally of the width of the prongs, intersecting said offsets and extending a short distance rearwardly of the prongs, thereby to provide longitudinally spaced shoulder portions respectively adapted to cooperate with portions of different types of electrical outlets for resisting separation of the connector plug from such outlets.

4. A connector plug according to claim 3 wherein the transverse offset on each prong comprises rearwardly facing side portions arranged to form an obtuse, rearwardly facing angle, whereby said angularly disposed side portions are adapted to fit portions of the terminals of a conventional type of electric outlet.
